UNITED STATES PATENT OFFICE.

DAVID C. JOHNSON, OF JOHNSON, NEW MEXICO.

CLAMP FOR WINDMILLS.

1,247,117.

Specification of Letters Patent. Patented Nov. 20, 1917.

Application filed April 12, 1916. Serial No. 90,797.

To all whom it may concern:

Be it known that I, DAVID C. JOHNSON, a citizen of the United States, residing at Johnson, in the county of Union and State 5 of New Mexico, have invented certain new and useful Improvements in Clamps for Windmills, of which the following is a specification.

The present invention relates to clamps 10 for windmill heads, water troughs and tanks, and consists in the combinations and arrangements of elements hereinafter described and particularly set forth in the accompanying claim.

15 The invention has for its purpose to provide a device of this character for clamping and plumbing the windmill head on top of the tower whereby the timbers of that portion of the structure may be firmly and rigidly secured, and adjusted to suit existing conditions. The clamp is also serviceable for use in making water troughs and tanks for stock and for various other purposes evident from the construction disclosed herein.

20 25 The invention has for its further purpose to produce a device of the character in question which may be readily applied to the usual fixtures or equipment supplied with windmills without in any manner altering 30 the latter or requiring special skill for its application.

Referring to the drawings forming a part of this specification, in which like figures designate like parts in the several views,

35 Figure 1 illustrates an ordinary windmill with the invention applied thereto.

Fig. 2 is a detailed top plan view of the clamp.

Fig. 3 is a side elevational view of the 40 same, and

Fig. 4 is a detailed perspective view of one of the clamp bars.

Referring to the construction in further detail 1, 2, 3 and 4 designate the corner posts 45 of the usual windmill structure and which will be hereinafter referred to as the windmill head or top of tower. Said members 1 to 4 are cut away, as at 5 to receive the usual pipe leading to the pump from the 50 well.

The clamp *per se* comprises four rods or bars 6, 7, 8 and 9 constructed from any suitable metal and preferably of that design shown in Fig. 4. Each of said bars has therefore a flat portion 10 and a reduced or shank portion 11 provided with threads 12.

And at its opposite end said flat portion is apertured to receive the shank portion of its connecting bar. At a point approximately midway of its length the flat portion of the 60 bar is further provided with a second aperture 14 to be presently explained.

In assembled relation the several bars are arranged against the opposite and outer faces of the windmill head after the manner 65 disclosed in Figs. 1 and 2, the shank portion of one bar passing through the apertured portion of the next bar and the several bars are then rigidly secured in assembled relation by nuts 15 threaded on said shank por- 70 75 tions as shown.

The four elements 1, 2, 3 and 4 are spaced to receive the filling pieces or blocks 16 and 18 which are designed to accommodate the different adjustments of the clamping bars. 75

It is contemplated to employ one of these clamps at a distance of twenty to thirty inches below the windmill head where the same is adapted to be secured to the usual spider by means of rods 19 or other devices 80 that connect with said spider and pass through the apertures 14.

This application of the invention is shown by way of illustration in Fig. 1 of the present drawing.

85 From the foregoing it will be readily apparent that the windmill head and its appurtenant parts may be readily plumbed and rigidly secured. And that the clamp will thereafter easily permit any adjustment necessary.

It is obvious that those skilled in the art may vary the details of construction and arrangement of parts without departing from the spirit of my invention, and therefore I 90 do not wish to be limited to such features except as may be required by the claim.

Having thus described my invention what I claim as new and desire to protect by United States Letters Patent is:

100 The combination with a windmill head having four corner posts and provided with a spider, of a clamp therefor comprising a plurality of metal bars each having an apertured flat portion, and a reduced threaded portion at one end, and said flat portion of each bar having an aperture approximately midway of its respective ends, a plurality of wedge blocks interposed between the respective corner posts, said bars being assem- 105 bled in rectangular relation on said corner posts by having the threaded reduced por- 110 115

tions of the respective bars passing through the apertures in the flat portions of said bars, nuts securing said bars in assembled relation, and said apertures medially of the 5 bars adapted to receive the spider of the windmill structure, substantially as set forth.

Copies of this patent may be obtained for five cents each, by addressing the "Commissioner of Patents, Washington, D. C."

In testimony whereof I affix my signature in the presence of two witnesses.

DAVID C. JOHNSON.
